UNITED STATES PATENT OFFICE.

JOHN A. HALL, OF EAST ORANGE, NEW JERSEY, ASSIGNEE, BY MESNE ASSIGNMENTS,
TO WESTERN ELECTRIC COMPANY, INCORPORATED, A CORPORATION OF NEW YORK.

ADAPTER FOR IGNITION SYSTEMS.

1,284,660.

Specification of Letters Patent. Patented Nov. 12, 1918.

Application filed October 9, 1915. Serial No. 55,050.

To all whom it may concern:

Be it known that I, JOHN ALDEN HALL, a citizen of the United States, residing at East Orange, in the county of Essex and State of New Jersey, have invented certain new and useful Improvements in Adapters for Ignition Systems, of which the following is a full, clear, concise, and exact description.

This invention relates to the conversion of ignition systems, in which no master vibrator is employed, into systems in which a master vibrator may be used, said conversion being effected in the simplest possible manner.

15 In certain well-known ignition systems, such as the one commonly used on Ford cars, there is provided a switch which, in one position, connects one source of current in the ignition circuit, and in another position connects a second source of current to said circuit.

20 In such systems, if it is desired to operate the spark coils in connection with a master vibrator, it is usual to provide a second or auxiliary switch with said master vibrator. The addition of this second switch although quite expensive renders it possible for an unskilled person to properly make the connections for introducing said master vibrator into said ignition system. However, by the means provided in this invention, it is possible to dispense with this auxiliary switch and at the same time permit a layman to readily connect the master vibrator in any 25 ignition system.

30 In accordance with this invention there is provided an adapter which may be inserted in the base of the container for the induction or spark coils forming a part of the apparatus of an ignition system. This adapter comprises a body member of non-conducting material provided with suitable contact strips for making connections automatically with contacts on the induction coils and contacts usually located in the base of a container therefor. Suitable terminals and leading-out wires are provided for connecting the adapter in a circuit with the master vibrator.

35 Figure 1 is a perspective view of the adapter contemplated by this invention;

Fig. 2 is a sectional view of the adapter illustrated in Fig. 1, inserted in a container for the spark coils of an ignition system and diagrammatically showing other apparatus 55 usually included in such a system.

In the ignition systems shown in the drawings there are provided a plurality of induction or spark coils 1 suitably housed in a container 15. It is common in the art to 60 have the induction coils 1 independently removable with respect to the container 15 and each other, and they are adapted to be automatically connected in the ignition circuit, when inserted in said container, by means of contacts 2 provided upon the base of each coil contacting with suitable contact strips or members 3 located in the base thereof. By means of a two-point switch 4, which is 65 usually mounted in front of the driver, as on the dashboard of a car, a source of current 5 is adapted to be connected to the ignition system when such switch is in one position, and when moved to a second position a second source of current 6 is thereby connected 70 to the operating circuit of the ignition system. The spark coils 1 are connected to the respective spark plugs 8 and to the timer 9 in any well known manner, the drawing being merely schematic as to the relation of 75 these elements to each other.

It may be mentioned here that the switch 4 is usually complicated because it is designed to make a car thief-proof by rendering the ignition system inoperable under 80 certain conditions. In the construction of such switches it is common for the manufacturer to provide a lock mechanism which can only be manipulated by an individual kind of a key, thus preventing the starting 85 of the engine by an unauthorized person. The switch and wires connected thereto are inclosed within a container. These features necessarily make the switch 4 expensive and 90 inaccessible under ordinary conditions.

If it is desired to operate the spark coils 1 of the above described system in connection with a master vibrator, it is almost impossible for a layman to make the proper connections between said vibrator and the switch 4 as the peculiar construction of said switch 95 does not admit of its ready connection with 100

other apparatus. To overcome this difficulty, it is customary to use a master vibrator provided with an auxiliary switch. This auxiliary switch is objectionable because it 5 complicates the ignition system and is also quite expensive to provide.

My invention avoids this difficulty by utilizing an adapter 10 having a body portion 11 of non-conducting material suitable in 10 size to be inserted and lie at the base of the container 15.

On the top surface of the body portion 11 of the adapter is a contact strip 12 for each of the induction coils 1, said strips being 15 connected to a common bus strip, which terminates at one end in a terminal suitable for attaching a leading-out conductor 13. On the under surface of the body portion 11 is a second contact strip 14 adapted to 20 make connection with the contact strips 3 secured in the base of the container 15. The strip 14 is also provided with a leading-out wire 13. The wires 13 are intended to be connected directly to a master vibrator 7. 25 When the master vibrator is included in an ignition circuit by means of the adapter 10, the vibrating contacts of the individual vibrators may be short-circuited in any obvious manner, such, for example, as screwing 30 down the adjusting screws to substantially prevent vibration. The switch 4 is then enabled to perform its complete function as illustrated diagrammatically in Fig. 2.

From the above description it will be apparent that by the adapter contemplated by this invention an unskilled person may readily introduce a master vibrator for controlling the operation of a plurality of induction coils. Also, by means of this adapter, any 40 type of master vibrator is rendered suitable for use in any sort of an ignition system.

What is claimed is:

1. In an ignition system for explosive engines, a plurality of induction coils, a container therefor, a source of current supply for said induction coils, means in said container adapted to connect said induction coils with said source of current, a master vibrator, and means comprising a non-conducting body portion, a plurality of contact strips connected to a common bus strip secured to one surface of said body portion, and a bus contact strip located upon the opposite surface of said body portion relative 55 to said contact strips for connecting said master vibrator in circuit between said source of current and said induction coils without change in external wiring or connections.

60 2. In an ignition system for explosive engines, the combination with a plurality of induction coils, a container therefor, a source of current, contacts on said container connected to said source of current, and contacts carried by said induction coils adapted to coöperate with said first named contacts to connect the source of current to each of 65 said induction coils when it is inserted in the container, of a master vibrator, and a set of contacts comprising two groups each electrically connected to one of the terminals of 70 said master vibrator, said set of contacts being arranged for insertion in the container with one group bearing against the contacts on the container, and the other group bearing against the corresponding contacts on the induction coils, whereby the master vibrator is connected in a circuit including the induction coils and the source of current.

3. In an ignition system for explosive engines, a plurality of induction coils, a container therefor, a source of current supply, connecting means in said container and connecting means on said induction coils adapted to coöperate with the connecting means 80 in said container to connect said induction coils with said source of energy, a master vibrator and a connecting plate adapted to be inserted in said container between the connecting means therein, and the connecting 85 means on said induction coils to include said master vibrator in circuit between said source of energy and said induction coils.

4. In an ignition system for explosive engines, the combination with a plurality of 90 induction coils, a container therefor, a plurality of sources of current, contacts on said container, switching means for connecting said contacts to any of said sources of current, and contacts carried by said induction 95 coils adapted to coöperate with said first named contacts to connect the said switching means to each of said induction coils when the coil is inserted in the container, of a master vibrator and a set of contacts comprising two groups each electrically connected to one of the terminals of 100 said master vibrator, said set of contacts being arranged for insertion in the container with one group bearing against the contacts on the container, and the other group bearing against the corresponding contacts on the induction coils, whereby the master vibrator is connected in a circuit including the induction coils and the switching means.

5. An adapter for an ignition system comprising a non-conducting body portion, a plurality of contact strips connected to a common bus strip secured to one surface of said body portion, a bus contact strip located upon the opposite surface of said body portion relative to said contact strips, and conductors for making connection with said contact members.

6. In an ignition system for explosive engines, a plurality of induction coils, a container therefor, a source of current supply for said induction coils, means in said con-
